(57) **CLAIM**

The ornamental design for a stretcher as shown and described.

DESCRIPTION

FIG. 1 is a front perspective view of a stretcher.

FIG. 2 is a rear perspective view of the stretcher shown in FIG. 1.

FIG. 3 is a front elevational view of the stretcher shown in FIG. 1.

FIG. 4 is a rear elevational view of the stretcher shown in FIG. 1.

FIG. 5 is a top plan view of the stretcher shown in FIG. 1.

FIG. 6 is a bottom plan view of the stretcher shown in FIG. 1.

FIG. 7 is a right side elevational view of the stretcher shown in FIG. 1.

FIG. 8 is a left side elevational view of the stretcher shown in FIG. 1.

FIG. 9 is a front perspective view of a stretcher according to an alternative embodiment.

FIG. 10 is a rear perspective view of the stretcher shown in FIG. 9.

FIG. 11 is a front elevational view of the stretcher shown in FIG. 9.

(Continued)

FIG. 12 is a rear elevational view of the stretcher shown in FIG. 9.

FIG. 13 is a top plan view of the stretcher shown in FIG. 9.

FIG. 14 is a bottom plan view of the stretcher shown in FIG. 9.

FIG. 15 is a right side elevational view of the stretcher shown in FIG. 9; and,

FIG. 16 is a left side elevational view of the stretcher shown in FIG. 9.

The features shown in dashed lines throughout the drawings represent portions of the stretcher that form no part of the claimed design.
